UNITED STATES PATENT OFFICE

165,249

TUMBLER

Huntley H. Soyster, San Francisco, Calif., assignor to Owens-Illinois Glass Company, Toledo, Ohio, a corporation of Ohio

Application September 12, 1950, Serial No. 12,149

Term of patent 14 years

(Cl. D36—8)

To all whom it may concern:

Be it known that I, Huntley H. Soyster, a citizen of the United States, residing at San Francisco, in the County of San Francisco and State of California, have invented a new, original, and ornamental Design for a Tumbler, of which the following is a specification, reference being had to the accompanying drawings, forming a part thereof.

In the drawings:

Fig. 1 is a side elevational view of a tumbler, showing my new design;

Fig. 2 is a bottom plan view;

Fig. 3 is a sectional view taken along the line 3—3 of Fig. 1;

Fig. 4 is a fragmentary sectional view taken along the line 4—4 of Fig. 3; and

Fig. 5 is a perspective view thereof.

I claim:

The ornamental design for a tumbler, substantially as shown.

HUNTLEY H. SOYSTER.
